Patented Apr. 3, 1923.

UNITED STATES PATENT OFFICE.

MARTHA HALOWELL CONNOR, OF BALTIMORE, MARYLAND, ASSIGNOR TO THE TIN DECORATING COMPANY OF BALTIMORE, OF BALTIMORE, MARYLAND, A CORPORATION OF NEW JERSEY.

COMBINED CANDLESTICK AND FLOWER VASE.

Application filed April 26, 1922. Serial No. 556,627.

To all whom it may concern:

Be it known that I, MARTHA HALOWELL CONNOR, a citizen of the United States, and resident of Baltimore, in the county of Baltimore and State of Maryland, have invented certain new and useful Improvements in Combined Candlesticks and Flower Vases, of which the following is a specification.

10 This invention relates to a sheet metal candle stick and more particularly to a convertible candle stick and flower vase; and has special reference to the provision of a combined candle stick and vase made of sheet metal and manufacturable and marketable at a very low cost.

15 A principal object of my present invention comprehends the provision of a candle stick made from sheet metal and having parts which may be rapidly and cheaply produced at a very low figure and in which the parts may be rearranged by a simple manipulation to interchangeably provide a candle holder and a holder for artificial or 20 natural flowers.

25 A further principal object of the invention includes the production of a candle stick of the nature referred to in which the parts are interrelated and interconnected in a manner to provide a reinforced and strong sheet metal structure when used either as a candle stick or vase, the candle stick and flower vase provided being suitably ornamented to present a highly pleasing and 30 attractive appearance for ornamental household use.

35 To the accomplishment of the foregoing and such other objects as may hereinafter appear, my invention consists in the elements and their relation one to the other, as hereinafter particularly described and sought to be defined in the claims, reference being had to the accompanying drawings which show preferred embodiments of my 40 invention, and in which:

45 Figure 1 is a perspective view of the candle stick and vase showing the same when used as a candle stick,

50 Figure 2 is a longitudinal cross sectional view thereof,

55 Figure 3 is a view thereof showing its use as a flower vase and showing a modification thereof, and

60 Figure 4 is a view of a detail.

Referring to the drawings, the sheet metal 55 candle stick of my invention comprises, essentially, the base B, the hollow post P carried thereby and the cup or receptacle C removably mounted on the post, the base, post and cup being fashioned from sheet metal 60 such, for example, as tin and being interrelated to effect an interchangeable candle stick and flower vase for household use.

The base B may be produced in any desired form, the form shown in the drawings 65 including the provision of a dished base stamped from a sheet metal blank, the base being preferably provided with a concave portion 10 centrally orificed to receive the post P, a flat annular portion 11 and a depending flange portion 12, the marginal edge of the flange portion 12 being provided with an ornamenting and stiffening outwardly rolled bead 13.

The hollow post P of the candle stick is 75 also made from a sheet metal blank and comprises a body portion 14 formed by rolling a metal blank into cylindrical formation, the meeting edges of the blank being joined together in a lock seam joint 80 15, the said lock seam joint extending substantially but not completely the full length of the body portion 14, the seam terminating at a point spaced a short distance from the lower end of the body portion, as shown 85 in Figure 4 of the drawings, the side edges such as 16 and 17 of the bottom end portion 19 of the post P being left unseamed. The post P is attached to the base B by inserting the same in the central orifice therein, an 90 annular outturned rib 18 being provided in the bottom end portion 19 of the post P for positioning the post on the base B, the remainder of bottom unlocked portion 19 of the post body being swaged under the concave portion 10 of the base B. With this construction the post P presents a hollow tubular member open at both ends thereof, the cross sectional area of the bottom end being substantially the same as the cross 100 sectional area of the top end, both ends being thus adaptable to interchangeably receive the same closure element.

The cup C is also preferably made from a sheet metal blank stamped or drawn to 105 produce the cup or receptacle portion 20 and the slightly tapering flange portion 21, the said flange portion 21 terminating in a

marginal bead 22. The cup C is intended as a closure element for either the top or bottom ends of the post P, the said cup being dimensioned to be frictionally receivable by and selectively insertible in the top and bottom ends of the post P. The cup C when frictionally fitted in the top end of the post serves as a candle holder, this use being shown, for example, in Figures 1 and 10 2 of the drawings; and the said cup when reversely inserted in the bottom end of the post P, as shown in Figure 3 of the drawings, functions as a closure for the said bottom end and as a support for one or more stems of artificial flowers or as a support for a holder 23 for natural flowers. The holder 23 may comprise a small glass tube as, for example, an ordinary test tube.

When the cup C is fitted into the top end 20 of the post P the said cup serves to reinforce the top marginal portion of the said post, a reinforced candle stick structure being thus provided. When the cup C is inserted in a similar manner in the bottom end of the post 25 P the said cup serves to brace and reinforce the attached post and base portions, the construction being such that the cylindrical receptacle portion 20 of the cup acts as a brace for the bottom portion of the post and the flange portion 21 and the bead 22 of the cup snugly engages the concave portion 10 of the base and acts as a reinforcement for the connection or joint between the post P and the base B, a strengthened flower vase 30 structure being thus obtained. The cup C may, if desired, be made of a heavier sheet metal stock than the post P so that the cup C may act as a weighting member for the base when the device is used as a flower vase.

If desired, the top marginal edge of the post P may be provided with an outturned bead 24 for reinforcing and ornamenting purposes, as shown in Figure 3 of the drawings. The outer walls of the candle stick and flower vase may be also suitably ornamented with any desired design as shown in the drawings, a highly pleasing and attractive ornamental household article being thereby 45 produced.

The manner of making and using my novel candle stick and flower vase will, in the main, be apparent from the above detailed description thereof. It will be further apparent that the base, post and cup of the device are all cheaply produced from sheet metal blanks fashioned into the desired configurations by simple manufacturing steps and assembled together in a simple manner, the device being made at a very low production cost and being capable of retail sale at an exceedingly low figure. It will be further seen that the device may be readily made to serve different ornamental household uses, either as a useful and ornamental candle stick or single stem flower vase.

While I have shown my device in the preferred forms, it will be obvious that many changes and modifications may be made in the structure disclosed without departing from the spirit of the invention, defined in 70 the following claims.

I claim:

1. As a new article of manufacture, a combined candlestick and vase comprising a base made of sheet metal, a hollow post open at 75 both ends and carried by the base, and a cup frictionally receivable by and selectively insertible in the post at either end thereof, the cup when inserted at the top end of the post functioning as a candle holder and when reversely inserted at the bottom end of the post serving as a bottom closure therefor and adapted for supporting a flower or flower holder.

2. As a new article of manufacture, a 85 combined candle stick and vase comprising a base stamped from a sheet metal blank, a tubular post formed from a sheet metal blank and attached to said base, the said tubular post being open at both ends and a 90 flanged cup stamped or drawn from a sheet metal blank, the said cup being frictionally receivable by and selectively insertible in the post at either end thereof, the cup when inserted at the top end of the post functioning 95 as a candle holder and when reversely inserted at the bottom end of the post serving as a bottom closure therefor and adapted for supporting a flower or flower holder.

3. A new article of manufacture comprising 100 a base stamped from a sheet metal blank, a tubular post formed by rolling a blank of sheet material into cylindrical formation and joining the side edges of the said blank by a lock seam joint extending from the top 105 of the post to a point adjacent the bottom thereof with the side edges of the bottom portion of the post left unlocked, the said post being attached to said base by swaging the said unlocked bottom portion of said 110 post to the base and a cup stamped or drawn from a sheet metal blank and receivable by an end of said post and forming a closure therefor.

4. A new article of manufacture comprising 115 a base stamped from a sheet metal blank, a tubular post formed by rolling a blank of sheet material into cylindrical formation and joining the side edges of the said blank by a lock seam joint extending from the top 120 of the post to a point adjacent the bottom thereof with the side edges of the bottom portion of the post left unlocked, the said post being attached to said base by swaging the said unlocked bottom portion of said 125 post to the base.

5. The herein described article of manufacture comprising a base stamped from a sheet metal blank and provided with a central orifice, a tubular post formed by rolling a 130

blank of sheet material into cylindrical formation and joining the side edges thereof, said post being provided with a peripheral rib or bead adjacent its bottom end, the said post being provided with a marginal flange at its bottom turned outwardly against the said base, the post being held locked to the

base by the said flange and peripheral rib, and a cup removably receivable by said post.

Signed at Baltimore, in the county of 10
Baltimore and State of Maryland, this 24th
day of April, A. D. 1922.

MARTHA HALOWELL CONNOR.
